UNITED STATES PATENT OFFICE.

CHARLES A. GAINES, OF NEW ORLEANS, LOUISIANA, ASSIGNOR TO
CHARLES MENDELSON, OF SAME PLACE.

APPARATUS FOR CARBONATING LIQUIDS.

SPECIFICATION forming part of Letters Patent No. 602,988, dated April 26, 1898.

Application filed June 18, 1897. Serial No. 641,323. (No model.)

To all whom it may concern:

Be it known that I, CHARLES A. GAINES, a citizen of the United States, residing at New Orleans, in the parish of Orleans and State of Louisiana, have invented certain new and useful Improvements in Apparatus for Carbonating Liquids; and I do declare the following to be a full, clear, and exact description of the invention, such as will enable others skilled in the art to which it appertains to make and use the same.

My invention relates to apparatus for carbonating liquids, and its preferred embodiment will be fully understood from the following description and claims when taken in conjunction with the annexed drawings, in which—

Figure 1 is a view of my improved apparatus complete, with some of the parts in section and others in elevation. Fig. 2 is a detail horizontal section taken in a plane above the pump, and Fig. 3 is an enlarged detail section taken in the plane indicated by the line *x x* of Fig. 2.

25 In the said drawings similar letters designate corresponding parts in all of the several views, referring to which—

A indicates the base of my improved apparatus, and B indicates the closed receiver or mixing vessel, which is suitably secured to the base. This vessel B has among its appurtenances a safety-valve *a* and water-glasses *b*, and it is provided at about the elevation shown with shafts *c d*, the former being provided with a sprocket-wheel *e* and a gear-wheel *f* and the latter being provided with a pinion *g*, which meshes with the gear-wheel *f*, and being also provided with a wheel *h*, having peripheral buckets *i*, for a purpose presently to be described.

35 C indicates a carbonic-acid-gas cartridge such as ordinarily used, which is provided with a discharge-valve *j* and is connected with the interior of the vessel B by a pipe *k*, leading from the valve *j* and equipped with a pressure-gage *l*.

40 D indicates a valved discharge-pipe for the carbonated liquid, which leads from the interior of the vessel B to a fountain or to a refrigerating device intermediate of the receiver and the fountain.

45 E indicates a pipe for conducting water into

the interior of the vessel B, which pipe has its discharge end so arranged as to discharge the water or other liquid against the buckets 55 *i* of the wheel *h*, and thereby cause said wheel to turn in the direction indicated by arrow, and F indicates an endless sprocket-chain of about the proportional length illustrated, which takes around and depends from 60 the sprocket-wheel *e* and is provided at intervals in its length with buckets *m*.

Water or other liquid to be carbonated is conducted under pressure into the vessel B through the pipe *E* and is discharged against 65 the buckets *i* of wheel *h*, so as to cause rotation of said wheel, and consequently cause the chain to travel in the direction indicated by arrow. In virtue of this it will be seen that when the cartridge *C* is connected with the 70 vessel B and the upper portion of said vessel is occupied by carbonic-acid gas, the buckets *m* of the chain *F* will raise the liquid and after passing over the sprocket *e* will discharge the same in showers. Consequently 75 the liquid and the carbonic-acid gas will be quickly commingled and the carbonating of the liquid will be materially accelerated. Again, it will be seen that after discharging the liquid the buckets *m* will be occupied by 80 carbonic-acid gas, which they will carry down into the body of the liquid, and thus further accelerate the carbonating of the same.

85 G indicates a force-pump, preferably a double-acting one, which may be of the ordinary or any suitable construction and need not therefore be specifically described. This pump, which may be operated by hand through the medium of a lever *n*, is connected by a pipe *p*, which may be equipped with a 90 meter *q*, with a water-main or other source of supply, and said pump has its discharge-chamber connected with the pipe *E*, said pipe *E* being preferably connected to the discharge air-chamber of the pump, as better shown in 95 Fig. 3. When the pump is operated, it will be seen that water will be drawn through the pipe *p* into its induction-chamber and will be discharged through its eduction-chamber and the pipe *E*, so as to fill the vessel B to the 100 proper height and at the same time drive the chain *F*. In this way the water in the vessel B will be carbonated while the vessel B is being charged with water. When a sufficient

quantity of water is placed in the vessel B, a three-way cock H, with which the pipe p is equipped, is turned so as to shut off communication between the pump and the water-main or other source of supply and establish communication between a pipe I, leading from the lower portion of the vessel B, and the induction-chamber of the pump G. At the same time the valve j of cartridge C is closed and the pump is then operated. When this is done, the water or other liquid will be circulated in a closed cycle from the lower portion of vessel B through pipe I, pump G, pipe E, to the upper portion of said vessel B, and will consequently be quickly commingled with the carbonic-acid gas contained in the vessel B, or, in other words, will be thoroughly commingled.

To further accelerate the thorough commingling of the gas and liquid, I provide the pipe J, which leads from the upper portion of the vessel B to the discharge-chamber of the pump. By reason of this pipe J it will be seen that when the pump is in operation and liquid is being forced through the pipe E gas will be siphoned from the upper portion of the vessel B through the pipe J and will be drawn into the discharge-chamber of the pump and the pipe E and carried by the latter back to the vessel B, being commingled with the liquid en route.

Having described my invention, what I claim, and desire to secure by Letters Patent, is—

- 35 1. In an apparatus for carbonating liquids, the combination of a closed vessel adapted to contain liquid and carbonic-acid gas, a liquid-elevator arranged in said vessel, a liquid-supply pipe leading from a source of supply into the closed vessel, and mechanism arranged to be operated by the stream of water from said supply-pipe and connected with the liquid-elevator so as to transmit motion to the same, substantially as specified.
- 40 2. In an apparatus for carbonating liquids, the combination of a closed vessel, a pump, a conduit leading from the induction-chamber of the pump to the closed vessel, a liquid-conduit connecting the induction-chamber of the pump and the closed vessel, a pipe J, connecting the upper portion of the closed vessel and the pump, and a water-elevator arranged in the closed vessel and operative by the stream of liquid from the first-named conduit, substantially as specified.
- 45 3. In an apparatus for carbonating liquids, the combination of a closed vessel adapted to contain liquid and carbonic-acid gas, a liquid-

elevator arranged in said vessel, a pump, a pipe leading from the discharge of the pump into the closed vessel, and mechanism arranged to be operated by the stream of liquid from said pipe and connected with the liquid-elevator so as to transmit motion to the same, substantially as specified.

4. In an apparatus for carbonating liquids, the combination of a closed vessel adapted to contain liquid and carbonic-acid gas, a liquid-elevator arranged in said vessel, a pump, a pipe leading from the discharge of the pump into the closed vessel, mechanism arranged to be operated by the stream of liquid from said pipe and connected with the liquid-elevator so as to transmit motion to the same, and a pipe connecting the closed vessel and the induction-chamber of the pump, substantially as specified.

5. In an apparatus for carbonating liquids, the combination of a closed vessel adapted to contain liquid and carbonic-acid gas, a liquid-elevator arranged in said vessel, a pump, a pipe leading from the discharge of the pump into the closed vessel, mechanism arranged to be operated by the stream of liquid from said pipe and connected with the liquid-elevator so as to transmit motion to the same, a pipe I, connected with the closed vessel, a three-way cock connected with said pipe I, and also with a pipe leading from a source of liquid-supply, and a pipe leading to the induction-chamber of the pump, substantially as specified.

6. In an apparatus for carbonating liquids, the combination of a closed vessel adapted to contain liquid and carbonic-acid gas, a pump, a pipe leading from the discharge of the pump into the closed vessel and a water-elevator arranged and adapted to discharge in the closed vessel and operative by the stream of water from the pipe, substantially as specified.

7. In an apparatus for carbonating liquids, a closed vessel forming part of a closed cycle, a pipe forming part of the closed cycle and having its discharge end arranged in the closed vessel, a water-elevator arranged in the closed vessel and operative by the stream of water from the pipe, and means for maintaining a circulation of liquid through the closed cycle, substantially as specified.

In testimony whereof I affix my signature in presence of two witnesses.

CHARLES A. GAINES.
